POST-MORTEM STERNUM CHEST PLATE
William H. Sorensen, Murdo, S. Dak.
Filed Oct. 1, 1962, Ser. No. 227,394
2 Claims. (Cl. 27—21)

This invention relates to a new and very useful post-mortem chest plate for cadavers.

In conducting post-mortem examinations of cadavers it is commonly necessary to explore the interior of the thoracic and abdominal cavities in the torso. For this purpose, it is the common practice to cut an oval hole in the rib cage through the front of the body, severing the ribs and sternum. However, following the examination, difficulty is experienced in returning the exterior of the chest to a normal position or appearance because of the lack of support for the sternum and attached bony and cartilaginous structures.

It is an object of this invention to provide a chest plate which conforms generally to the exterior shape of the chest cavity and which is shaped so as to rest upon and be supported by the severed ends of the ribs and the clavicle bones, thereby to provide a platform over which skin may be laid and sutured together along the incision lines therein. The result is to create in a cadaver which has undergone a post-mortem examination of the torso interior, a chest cavity having a normally expanded appearance.

It is another object of this invention to provide a method for reforming the chest of a cadaver which has undergone a torso interior post-mortem examination, so as to give such corpse a normal exterior appearance.

It is a further object of this invention to provide a post-mortem chest plate as a cover for an aperture through the rib cage in the chest of a cadaver, to provide a platform to support the chest skin in a position somewhat resembling its original viable shape.

Other and further objects of this invention will become apparent to those skilled in the art from a reading of the attached specification, taken together with the drawings, in which:

FIG. 1 is a top plan view of a human torso showing the manner of laying open the skin and rib cage for a post-mortem examination of the internal body organs (not shown), some parts thereof broken away;

FIG. 2 is a side elevation view of a thoracic cavity which has been opened in the manner shown in FIG. 1, and which is covered with the post-mortem chest plate of this invention, some parts thereof being broken away;

FIG. 3 is a top plan view of the thoracic cavity of a torso which has undergone post-mortem examination and which has been closed with the post-mortem sternum plate of this invention, some parts thereof broken away;

FIG. 4 is a top plan view showing the exterior appearance of a reconstructed torso containing within the thoracic region the post-mortem chest plate of this invention.

Turning to the drawings, there is seen in FIGURE 1 a torso 10 laid open for post-mortem examination in a conventional manner. An incision 11 is made extending vertically down the middle of the torso 10, beginning about one-third of the way down the (approximated) center line of the sternum and extending to the crotch or inguen 12. From the upper end of the elongated vertical incision 11 is made a pair of diagonal incisions 13 and 14, each running upwardly and outwardly from the upper end of the elongated vertical incision 11 at an angle of about 120°. Each diagonal incision 13 and 14 extends to respective clavicles 26 and 27. The skin and associated tissue and musculature immediately associated therewith is then folded back to form folds 15 and 16,

2

thereby exposing the musculature and skeletal structure lying therebeneath.

Such examination of the musculature as is desired is then made. To enter the thoracic cavity it is necessary 5 to cut away a portion of the rib cage. This is conveniently accomplished by severing the sternum 28 crosswise at about line 29 and then severing each rib approximately in the region where the bony structure of the rib ends and the costal cartilage begins. Thus, the seven 10 true ribs which are connected directly to each side of the sternum and the three false ribs which are not directly connected to the sternum but are indirectly connected thereto by means of costal cartilaginous linkages, are all severed. Unless already removed in the process of cutting 15 through the rib cage, the following muscle pairs are cut (in descending order): the latissimus dorsi, the obliquus externus abdominis, and the rectus abdominis.

The resulting ovate or elliptically shaped bony and cartilaginous section is then lifted out and post-mortem 20 examination of the internal organs is conducted as desired. This ovate bony section includes the lower end of the sternum, costal cartilages, and associated rib ends. At the conclusion of the examination, the various organs and tissues which may have been removed are usually 25 replaced and the ovate bony and cartilaginous section is set back in place.

However, as those familiar with the human body will appreciate, there is no supporting internal structure upon 30 which to rest the ovate bony and cartilaginous section. Consequently, without some extraneous or supplemental supporting means, the folds of skin 15 and 16, were they to be returned to their normal position and sutured together, would form a sagging region in the position where 35 the chest is normally rounded and expanded across the region of the sternum.

To correct this situation and restore the shape of the 40 rib cage and that of the exterior chest appearance to something resembling that in the normal homo sapiens, there is provided the chest plate 17 shown in top view in FIGURE 3 and in side view in FIGURE 2. This chest plate 17 is generally bilaterally symmetrical along a lengthwise, running hypothetical center line. The plate 17 itself, when viewed from an end, has an exterior surface which is convex and shaped generally so as to conform 45 to a normal torso curvature. The top mid-region is dished out or cut away concavely, as when viewed in top plan, leaving a pair of peaks or points 18 and 19 on either side. Laterally of each respective peak 18 and 19, along the top sides of the chest plate 17, is an expanded or 50 bowed region numbered 20 and 21 respectively (paired). These expanded regions 20 and 21 serve to fill out the chest region in the domain roughly between the respective scapulas 30 and 31 and the sternum, because, the 55 musculature in this region having been severed as above described, would otherwise sag in an abnormal or unnatural manner. Opposite corners across the bottom region of chest plate 17 downwardly protrude to form protuberances 22 and 23. The bottom center 24 of chest plate 17 is dished in a concave manner, as when viewed in top plan.

When mounted over the ovate hole in the rib cage of a 60 cadaver, peaks 18 and 19 rest on the respective clavicles 26 and 27, these bones having been left joined to the top end of the sternum 28 for this purpose. The lower opposite side edges of the chest plate 17 below the bowed 65 regions 20 and 21 rest upon the severed ends of the ribs in this region.

Once the chest plate 17 is in position, the folds of skin and tissue 15 and 16 are folded back or placed over chest 70 plate 17. Conveniently, skin edges are fastened together as by suturing, in the manner shown in FIG. 4, clipping, or the like, over chest plate 17. The chest plate 17 not

only serves to restore the chest to a normal appearance but also serves as a platform upon which suturing is readily accomplished. Observe that the dished portion 24 in the bottom center region of chest plate 17 serves to allow the abdominal region to have a normal appearance exteriorly in the so remodeled cadaver.

Also observe that should the clavicles and associated intervening top portion of the sternum, for some reason, be separated before the chest plate 17 is placed in position, such as, for example, could happen when the bony structure of the torso is badly damaged, morticians using ordinary skill in the art can artificially reposition the clavicles and sternum in their approximate positions, or use their artificial equivalents, so as to permit use of the chest plate 17 of this invention to cover the chest aperture. Similarly, if the false rib ends used to support the bottom sides of the chest plate 17 are dislocated or even removed, morticians using ordinary techniques known to the art can reposition such rib ends so as to permit use of the chest plate of this invention. Consequently, the chest plate of this invention is adaptable for use in a variety of ways by morticians.

In general, chest plate 17 is formed from resilient, self-supporting material, preferably thin. Conventional plastic materials can be used, such as polyethylene, polyvinyl chloride, etc.

In summary, the present invention relates to a post-mortem chest plate formed from resilient self-supporting material and adapted to be positioned between the rib cage and the skin of a cadaver, said plate being bilaterally symmetrical and having a top surface curved to resemble the appearance of a normal chest, peaked upper corner portions adapted to rest upon respective clavicles of said cadaver, upper opposite side edges outwardly bowed, downwardly sloping lower corner portions adapted to rest upon the ends of the lower ribs of said cadaver, and upper and lower concave edges intermediate said upper and lower corner portions, respectively.

The invention also relates to the method for restoring the chest of a cadaver to a normally expanded appearance following a post-mortem examination of the interior of the thoracic cavity. This method involves the steps of positioning a plate of resilient material and having a top contour resembling the normal shape of the chest

over the chest aperture formed in the rib cage during said post-mortem and disposing the upper corner portions of said plate on the adjacent clavicles of said cadaver and the lower corner portions of said plate on the ends of the lower ribs of said cadaver, and thereafter covering said chest plate with the skin of said cadaver.

This invention has been thoroughly tested and found to be completely satisfactory for the accomplishment of the above objects, and while I have shown and described a preferred embodiment, I wish it to be specifically understood that the same is capable of modification without departure from the spirit and scope of the appended claims.

The claims are:

15 1. A post-mortem chest plate formed from self-supporting sheetlike material and adapted to be positioned between the rib cage and the skin of a cadaver, said plate being bilaterally symmetrical and having:

- (a) a top surface curved to resemble the appearance of a normal chest,
- (b) peaked upper corner portions adapted to rest upon respective clavicles of said cadaver,
- (c) upper opposite side edges outwardly bowed,
- (d) downwardly sloping lower corner portions adapted to rest upon the ends of the lower ribs of said cadaver, and
- (e) upper and lower concave edges intermediate said upper and lower corner portions respectively.

20 2. A post-mortem chest plate formed from resilient self-supporting material and adapted to be positioned between the rib cage and the skin of a cadaver, said plate being bilaterally symmetrical and having:

- (a) peaked upper corner portions adapted to rest upon respective clavicles of said cadaver,
- (b) upper opposite side edges outwardly bowed,
- (c) downwardly sloping lower corner portions adapted to rest upon the ends of the lower ribs of said cadaver, and
- (d) upper and lower concave edges intermediate said upper and lower corner portions respectively.
